UNITED STATES PATENT OFFICE.

JULIUS DORNETH, OF BERLIN, GERMANY, ASSIGNOR TO TYPOGRAPH G. M. B. H., OF BERLIN, GERMANY.

TYPOGRAPH COMPOSING-MACHINE.

1,072,927.

Specification of Letters Patent. Patented Sept. 9, 1913.

Application filed July 26, 1907. Serial No. 385,672.

To all whom it may concern:

Be it known that I, JULIUS DORNETH, work-master, a citizen of the Kingdom of Prussia, residing at No. 29 Nostitz street, Berlin, S. W., Germany, have invented certain new and useful Improvements in Typograph Composing-Machines; and I do hereby declare the following to be a full, clear, and exact description of the invention, such as will enable others skilled in the art to which it appertains to make and use the same.

The present invention relates to improvements in the typograph composing machine, and an important object is means for adjusting the matrix-bars which make the composed line. The working faces which come into the question when adjusting the bars are arranged in such a manner that splashes of lead, dirt, dust and the like are not deposited on these working faces and can not prevent them from being adjusted exactly. The adjustment is effected by the matrices being first set in a horizontal and then in a vertical direction. These means in accordance with the present invention are particularly suitable for machines having two and more sorts of type.

In order that the invention may be clearly understood reference is made to the accompanying drawings in which one embodiment for two sorts of type is represented by way of example, and in which:

Figure 1 is an elevation of the fixed frame of a composing machine and a longitudinal vertical section through the matrix-basket; Figs. 2 and 3 represent a matrix-bar and the parts used for adjusting the same on a considerably larger scale; Fig. 4 is a plan of the frame of the machine on an enlarged scale, and Figs. 4^a and 4^b respectively a detail view of the eye b, Fig. 4, and a diagram showing the positions of the matrix bars in composing. Fig. 4^c a detail view in perspective, of parts shown in Fig. 4. Fig. 5 is a section in the plane I—I in Fig. 4; Figs. 5^a and 5^b show details of Fig. 5 in other positions. Fig. 6 is a front elevation on an enlarged scale of part of the matrix-basket after the same has been partially turned up; Figs. 6^a and 6^b detail views of parts shown in Figs. 4 and 6; Figs. 7 to 9 show details on an enlarged scale of the parts which are moved by the space key; Figs. 10, 11

and 12 are detail views, the first in plan and the two latter in elevation, of the flag-staff and adjacent parts; and Figs. 13 and 14 are side elevations of a matrix bar used in connection with this invention, showing two different adjustments of the same.

Similar reference numerals denote similar parts in all views.

Referring to the drawings, A is the matrix-basket which is fixed firmly on a shaft 1 adapted to slide or to be shifted longitudinally in its bearings 22 (see Fig. 4). This shaft 1 is also mounted to rock in bearings 22 (Figs. 1 and 4) on the stationary frame B of the machine, thereby enabling the matrix basket A to be swung or rocked in and out of its operative position, indicated in Fig. 1, by grasping the handle 6, Fig. 1. By pressing on one of the keys 2 the corresponding matrix-bar 4 which is suspended above in the matrix-basket is released by means of the wire 3. It slides on its guide wire 5 down to the assembling place where the line is composed and then cast. The basket is then swung upward by means of the handle 6 by rotating the shaft 1 in its bearings, so that all the matrix-bars slide back again on their wires 5.

New in order to be able to exactly adjust the matrix-bars 4 at the assembling place, they are first adjusted in a horizontal direction, that is to say they are put into a straight line, and are then adjusted in a vertical direction. For this purpose the matrix-bars are provided in front at the bottom end with an incision or notch 7 and at the rear with a notch 8 (Fig. 2). There is a fixed strip 9, which serves as an alining or composing guide, on the frame B which engages in the notch 8 as soon as the matrix-bars are adjusted at the assembling place.

The matrix-bars are adjusted in the horizontal direction by means of a compressing bar or flagstaff, 25, best shown in Fig. 1 and also shown in its operative and inoperative tilted positions respectively in Figs. 2 and 3, on which compressing bar or flagstaff there is a fillet or strip 26, said flagstaff being mounted on an axle 27 as shown. When the machine is thrown into gear by pressure on the coupling-rod 16 (Figs. 1 and 6), after composing the line, the "flagstaff" is swung upward around its axle 27.

The form, arrangement and operation of

the flag-staff in connection with axle 27 will be apparent from an inspection of Figs. 10, 11 and 12. Fig. 10 is a plan view showing the flagstaff or clamp 25 turned 5 down into a horizontal position and out of the way of the line of matrix bars 4, as shown. When, however, the line of matrices is set up as stated, the pressure on the coupling rod rocks the flag-staff on its 10 axle 27 into the position shown in Fig. 11, which is an elevation of the flag-staff when occupying a vertical position. The fillet 26 engages in the notches 7 of all the matrix-bars 4 (see Fig. 2 in particular), and adjusts and alines the matrix-bars so that they lie in one plane. If one of the bars has become placed aslant when it was being composed, because it was not suspended perfectly from its wire for example, the notch 20 8 will not lap over the strip 9, but, as Fig. 3 shows, the bar will abut against the strip 9; the fillet 26 cannot engage in the notch 7 and cannot adjust the line. Further, the machine cannot then be thrown 25 into gear because the "flag-staff" cannot go into its final position. The compositor then sees this defect at once and can set the matrix-bar correctly. When the matrices and spaces are all set up the spaces 30 between the matrices are expanded to the proper degree and the flag-staff 2 is moved from its dotted position, Fig. 12, to the full-line position in the same figure. Thereby the matrices and intervening spaces are 35 properly compressed for casting purposes.

On the mold-holder 10, which carries the mold 10', of the form and construction usual in typegrap^{as} and which is adapted to rock on the shaft 23 (Fig. 5), there is a dog 11 40 adapted to turn on the pivot 24 on the mold-holder in such a manner that when the machine is thrown into gear, the lever 11 engages with its point in a notch 7' of the matrix bar opposite to it and raises the said 45 matrix-bar somewhat with its upper face 7², the mold-holder having been coincidentally rocked toward the matrix-bars after they have been adjusted and alined horizontally, as indicated in dotted lines in Fig. 5. The 50 means for rocking the mold-holder are represented in Fig. 5. They consist of a lever 10² pivoted at 10³ to the machine frame and connected to the wrist pin 10⁴ of a crank-wheel 10⁵ by a pitman 10⁶, connected to lever 55 10² by an articulation 10⁷, the upper end of the lever 10² being connected to the heel of the mold-holder 10 by a link 10⁸. When the mold-holder and the mold 10' have been 60 swung upward into the position indicated in dotted lines, the melting pot, which is of a form well-known and the particular construction of which forms no part of the present invention, is swung upward so that its nozzle 7⁴, indicated in dotted lines in 65 Fig. 5 abuts against and closes the mold 10',

as shown. The line can then be cast. The lower face of the notch 8 is by this means pressed against the bottom side of the strip 9, (see the dotted lines in Fig. 2) and the matrix-bars are thereby adjusted exactly 70 lengthwise. Heretofore in machines of this character, the upper faces of the notches were pressed against the upper side of such strip. By such an arrangement this strip, during use, gradually became coated on its 75 upper face with the dirt, impurities and lead particles which by careless cleaning of the machine collected thereon. Such dirt and foreign matter cannot collect on the under surface of the strip, and hence the same will, 80 under the present arrangement, always serve as an accurate alining guide, which is not the case where the notches are pressed against the upper face of such strip. The upper face of the lever 11 engages exactly 85 in the notch 7' and presses the matrix-bars against the lower edge of the strip 9 and thus assures that they lie closely together in every case. This arrangement is particularly preferable if each matrix-bar is to have 90 several matrices, in order to make possible a change in the sort of type in the case of a machine with several sorts of type.

In the drawing a machine with two sorts of type is represented by way of example, so 95 that it is possible, for example, to employ full-faced and slender-faced type as desired. Thus each of the matrix-bars carries two matrices 12, 13, of which 12 forms the slender and 13 the full-faced type. There must 100 then be two corresponding incisions or notches in the front and rear longitudinal edges. If the upper matrix 12 for slender-type is to be cast, the matrix-bar must take up the position represented in Fig. 2; the 105 notches 7' and 8 then come into action. If the lower matrix 13, for full-faced type, is to be cast, the bar must be raised so that the lever 11 then engages the notch 7 and the strip 9 correspondingly a notch 8'. It suffices for the operation of the fillet 26 that 110 the bottom corner of the matrix-bar is bevelled off as shown at 7². The suspension-eye of the matrix-bar is revoluble or articulated in known manner, and is arranged so that it 115 can be turned through 90°, so that the bars can be raised without the same having to leave their wires. This arrangement of the articulated eye of the matrix-bar is shown 120 in Figs. 13 and 14, the eye 4² being shown in its upright position in Fig. 13 and in its bent over position in Fig. 14. In the first case upper matrix 12, in the second, the lower matrix 13 is brought into casting position, as will be understood.

When a line of mixed type is to be cast, that is to say, in case some of the matrix bars, 4, of the said line are to be raised to bring the matrices 13 instead of the matrices 12 into casting position, the matrix-basket 130

is first coupled, that is to say, displaced laterally toward the fixed frame B. Consequently the strip 9 will occupy a position relatively to the said matrix-bars that, as these bars are tripped or released by the depression of the corresponding keys, they will engage the said strip, 9, either with their notches 8 or their notches 8', as indicated in Fig. 2, such engagement depending 10 on whether the said bars have been raised by traveling over the inclined rising track 14, or not. When the basket is coupled and it is desired to compose a word, of ordinary or slender type, this is done as above, in the 15 ordinary way. The strip, 9, will then engage with the notches 8. If, however, a word is to be set up in distinctive full face type, the inclined track, 14, and the pin, 15, are thrust forward by the means hereinafter 20 described. The pin 15, prevents the matrix-bars, 4, from passing to the strip 9 and thus they are detained in front of the composing or alining guide and the inclined track, 14, serves to raise the bars so as to present the 25 lower matrices 13 in the casting position. Thus the type bars for a word to be cast in distinctive full faced type will find place on the inclined surface of the track, 14, in front of pin, 15. When the composition of 30 the word has been completed, the pin 15 is withdrawn and the matrix-bars for the entire word are then simultaneously pushed onto the strip, 9, by means of the lever 66, shown in Fig. 1, the said strip, 9, engaging 35 the notches, 8', of these matrix-bars.

The manner in which the matrix-basket or bank A is coupled or shifted laterally toward the fixed frame, B, will be clear from the following description, particular reference being had, for this purpose, to Figs. 1, 4, 5 and 6.

Referring now to Fig. 4 it will be seen that on the shaft 1 there is shiftably mounted a hub or sleeve, a, from which extends 45 upwardly an eye, b, represented in elevation in Fig. 4^a. Through this eye passes the end of the threaded spindle c which is secured to one end of the tensile spring 28, the other end of said spring being attached at 28' to 50 the bearing 22 for said shaft 1. The threaded end of this spindle is engaged by a thumb-nut d by means of which the spring is held in position and which serves to regulate the degree of tension of the spring 28, whose 55 tendency is to shift the hub and with it the matrix basket in the direction of the arrows in this figure. On the hub a the matrix-basket A is mounted through the medium of the arm or bracket, A' (see Fig. 1), said 60 arm A' being attached to and extending upwardly in an inclined direction from the said hub. The hub a is connected by the rod 29 with the lever 30 of the first class fulcrumed at 31 (Figs. 1, 4 and 5). The 65 hub, a, and with it the matrix bank or basket

which it carries, are shifted to the operative or inoperative position, that is to say, to the right or to the left, and held in these positions, which I term the coupled and uncoupled positions, by the following means 70 and instrumentalities: An arm 32 (Figs. 1 and 5), which lies with the one end 32^a against a fixed pulley 33, and which is adapted to rock on a pivot 32^b, is pivoted at 32^c at the end of the lever 30. Consequently the lever 30 is prevented from rocking. The spring 28 in this position of the parts cannot displace the shaft 1 and with it the matrix-basket in the direction of the arrow (Fig. 4); and the matrix-basket stands 75 so far away from the fixed frame that the matrix-bars pass freely to the strip 9, and the latter can then engage in the notches 8, 8' of the matrix-bars when the machine is thrown into gear and the basket is pushed 80 to the right-hand.

The matrix-basket is moved toward the fixed frame by rotating the coupling-rod 16 (Figs. 4 and 6). There is a cam 17 mounted at the lower end of coupling rod 16, as shown 90 in Figs. 1 and 4, which has a slanting face 34 on one side. When the cam is rotated in the direction of the arrow (Fig. 4), the face 34 acts on a rod 35 (Fig. 1) and presses it downward; the end of this rod 35, presses 95 on the end 32^c of the arm 32 (Figs. 5, 5^a, 5^b), and moves this end downward, thereby rocking the arm 32. Consequently the arm 32 being now disengaged from the roller 33, the lever 30 is unlocked and since this lever 100 is connected to the basket A the spring 28 can now operate and displace the shaft 1, so that the collar 70 of the same lies against the bearing 22. In consequence of the displacement of the shaft 1, the entire basket 105 is displaced, and the two-armed lever 30 is rotated, so that the arm 32 lies with its end 32^a on the pulley 33. The arm 32 thus acts as a lock against the tension of spring 28.

In Fig. 4 the full lines represent the shaft 110 1 and the hub a carrying the matrix-bank in its left hand or uncoupled position, while the right-hand or coupled position of these parts is indicated in dotted lines in this figure.

A hook-shaped lever 37 is pivoted on the 115 mold-holder 10 (Fig. 5). When casting is finished and the mold-holder has rocked away from the matrix-bars, the hook 37 is drawn forward from the dotted line position, Fig. 5, to the full line position until 120 it strikes against a correspondingly shaped stop 38 of the two-armed lever 30 (Figs. 4 and 5). This lever is thereby rocked until the end 32^c of the arm 32 slides off the pulley 33 and lies against the same. A 125 spring which is not represented in the drawing is arranged inside the lever 30 which sets the arm 32 horizontally again after it has slid off the pulley 33. The matrix-basket is thrown into gear against the ten- 130

sion of the spring 28 by the rocking of the two-armed lever 30. The hook 37 on which there is a nose 37' slides over a pulley 42 which is fixed on the machine frame; now when the nose 37' of the lever 37 strikes the pulley 42, the hook 37 becomes disengaged from the stop 38, leaving said stop 38 in the position indicated in full lines in Fig. 5. When the mold carrier 10 is again tilted upward into its casting position the hook 37 rides over the pulley 42 being elevated sufficiently thereby to resume, at the end of its stroke, in the position indicated in dotted lines in Fig. 5, the operations hereinabove described for tripping the arm 32 and the stop 38.

It sometimes happens that, after a line has been cast, the same line has to be cast again. For this work of recasting it is, of course unnecessary to redistribute and re-compose the line, and hence the mechanism must be so arranged that such casting operation may be repeated without disturbing the line. Now when the line to be cast is a line of mixed type, the act of swinging the mold-holder, 10, from the operative position in dotted lines to the inoperative position in full lines, Fig. 5, after the first line has been cast, for the purpose of removing said line, would cause the hooked lever to engage the stop, 38, thereby rocking the lever 30, as described above, and shifting the matrix-basket so as to cause all of the matrix-bars, 4, to recede from the strip, 9, whereby all of those matrix bars presenting the lower matrices, 13, having been raised into such position by the inclined or rising track, 14, would drop and the line would have to be reset. In order to avoid this, a lever 39 which can be rocked by hand or foot is provided (Figs. 1, 4 and 5). On this lever there is a sliding-piece 40 which is guided in a slot of the two-armed lever 30, as best shown in Fig. 4. The upper face 41 of this slider 40 is formed in the shape of an arc (Fig. 5^b). Now if the lever 39 (see Figs. 1, 5, 5^a and 5^b) is depressed, the slider 40 is raised in the slot of the lever 30, so that the curved face 41 is set in front of the stop 38. Now when the mold-holder is rotated backward, the hook 37 slides over the face 41 and cannot then become coupled with the stop 38 and drive the lever 30; accordingly the matrix-basket is not thrown out of gear.

When the coupling-rod 16 or the cam 17 is rotated, the slanting face 14 and the pin 15 are to be simultaneously pushed forward into the path traversed by the matrix-bars. The cam 17 presses against the sliding-carriage 19 (Figs. 1, 4 and 5) when it is rotated and the latter lies against the one arm of a two-armed lever 18. The latter extends through the opening of a carriage 14'

indicated in dotted lines in Fig. 5. This carriage has guide slots 14² which engage guide pins which extend into the same from the frame of the machine. To the carriage 14 is rigidly secured the face 14. By these means the face 14 is guided rectilineally in such a manner that it is pushed forward (see the dotted position in Fig. 4) or backward by rocking the lever 18. When the coupling-rod is rotated backward and when the cam 17 no longer lies against the carriage 19, a spring 43 draws back the slanting face 14.

The pin 15 is pushed forward by the matrix-basket A itself. A two-armed lever 44 (Figs. 6 and 6^b) is revoluble on the latter and passes through a slot 45 of a peculiarly shaped lever 46. On the basket A is mounted an arm 46' which carries the pivot 46² of the lever 46, as shown in Figs. 6^a and 6^b of the drawing. A shoulder or stop 47 of this lever engages in the notch 48 of a rod 49 (see Figs. 4, 6^a and 6^b). The pin 15 is connected with a two-armed lever 20 which is pivoted at 50, as best shown in Fig. 4. The end of this lever is bent up angularly to form a slanting face 51. The lever 46 rests against the end of this lever 20 as shown in Figs. 4 and 6^a. Now when the basket is put into gear by rotating the coupling-rod 16, the pivot 46² of the lever 46 is concurrently shifted, whereby the said lever 46 is rocked on its end engaging the notch 48 until it is somewhat withdrawn from the end of the lever 44 (Figs. 4 and 6^b). Thereby the said lever 46 presses against the end 51 of the lever 20, rocking the latter to the right and causing the pin 15 to be pressed forward to the left (Fig. 4).

The pin 15 must be pulled back every time as soon as a word is composed in one sort of type and has to be pushed on to the strip 9. This is effected by depressing the space-key 21. The latter presses, by means of a rod 63, on the end of a lever 62 (see Figs. 4 and 6^a). One arm of this lever is connected to a rod or bar 64, best seen in Figs. 4 and 6^a, which rod or bar is formed at its free end with hook 64' which passes over and engages the lever 20, which actuates the pin 15 in such a way that, on depressing the rod 63, the lever 20 is rocked to withdraw the pin 15, through the medium of the said rod or bar 64, which is withdrawn toward the right as the said rod 63 is depressed, as will be apparent from an inspection of Fig. 4 taken in connection with Fig. 6^a. By thus withdrawing the pin 15 the tension on the spring 52 is released. As shown in Figs. 4 and 4^a, the pin 15 is for this purpose provided at its end with a head 15' having a lateral slotted tongue 15² which is engaged by the rod 49 and bears at one end against the end of the lever 20. Thereby the movement of the lever 20 causes the longitudinal move-

ment of the pin 15. The matrix-bars are then pushed on to the fixed strip 9 by a device which is described hereafter.

As best shown in Figs. 4 and 6^a, the rod or bar 64 is pivoted at its one end on a boss extending from the rear of rod 49, one arm of the lever 62 being jointed to the rear of said rod 49, at 49' as best shown in said Figs. 4 and 6^a. A coiled spring 65 encircles the rod 49 and bears at one end against the fixed post 65' and at the other against an abutment 65² on the rod 49, thereby tending to urge the said rod 49 forward to the left in Figs. 4 and 6^a. By pressing on the rod 63, therefore, the outwardly extending arm of the lever 62 is depressed, thereby pulling back to the right the rod 49 and putting spring 65 under tension. By thus pulling back the rod 49, the lever 46 is rocked on its pivot 46², which is made possible by the fact that the lever 46 has been somewhat withdrawn from lever 44 on part 48. When the pressure of the rod 63 on lever 62 is released, the spring 65, being also released, returns the rod 49 to its original position, thereby rocking the lever 46 on its pivot 46², thereby, through the medium of the lever 20, returning the pin 15 to its original forward position, against the stress of the weaker spring 52.

When a line of mixed matter is entirely composed, the pin 15 must be withdrawn so that the machine actuating mechanism can be thrown into gear because otherwise the parts which move during the casting operation would strike against said pin 15. This is effected, at the same time that the machine is put into gear, by pressing on the coupling-rod 16. The latter is for this purpose provided with a hook 54 (Fig. 6) which engages the two-armed lever 44. Now if the rod 16 is depressed, the hook is also pulled down with it and the lever 44 is rocked. Consequently the end of the lever 46, which is provided with the slot 45, is raised so far that the arm 51 can pass below the lower edge of the lever 46. Consequently the two-armed lever 20 is rocked under the action of the spring 52 and the pin 15 is withdrawn. If the pressure on the coupling-rod 16 is then released, the hook 54 rises again, the lever 44 rotates backward, and the lever 46 is thereby depressed, so that its lower edge lies on the slanting face 51. When the machine is then thrown out of gear after casting, the lever 46 slides on the slanting face 51 until it lies behind the same; so that when the matrix basket is thrown into gear again the pin moves forward again.

Every time the pin 15 is withdrawn during the composing of a line, that is to say every time the space-key 21 is depressed the matrix-bars suspended in front of the pin 15 must be simultaneously pushed on to the fixed strip 9. This is likewise effected by

pressing on the space-key 21, whereby an arm 66, as is represented in Fig. 1 in dotted lines, is depressed in such a manner that it pushes the matrix-bars on to the strip 9. The space-key lever 21 (Figs. 7, 8 and 9) is formed angularly and has a slot 55 in its lower limb. In the fixed frame of the machine there is a hole 56 (Fig. 4) in which the end of a rod 57 engages. This rod is connected with a lever 58 which is provided with a slot 59 and which is fastened to the key-board. In consequence of the displacement of the matrix-basket the rod 57 is rotated around its end which is in the fixed frame, and the lever 58 is thereby displaced in the direction of the arrow (Fig. 7). Its end then engages in the slot 55 of the space-key 21. Thus as soon as the basket is thrown into gear, the lever 58 and the rod 57 are coupled with the space-key 21. When the basket is thrown out of gear the lever 58 goes out of the slot 55 and uncoupling takes place. Now if the space-key is depressed in the coupled state, the lever 58 is thereby rocked around its fulcrum 60. The other end of this lever operates on a rod 61 (Fig. 1) and presses the latter against an arm 66 which consequently flies downward and pushes the matrix-bars on to the strip 9.

The manner in which the machine operates is as follows:—If simple matter is to be composed, the matrix bank or basket A is thrown out of gear, that is to say, it is shifted to the left, to the position indicated in full lines in Fig. 4 in the manner and by the means hereinbefore described. The slanting face 14 and the pin 15 are then withdrawn. The matrix bars then go at once to and are alined in the proper position for casting. They are thus brought to occupy the position with reference to the alining strip 9 on the frame B which is indicated by the dotted lines in Fig. 4^b. During this composing of the matrices the machine, of course, remains uncoupled or out of gear. After the line has been composed, then the machine is thrown into gear or coupled with the power shaft by pressing on the coupling rod 16 hereinbefore described. The cam, 17, mounted on this rod 16, thereby bears directly on the rod 35 and through it on the catch arm 32, which as above described, releases the lever 30, thereby permitting the spring 28 (Fig. 4^a) to shift the matrix bank or basket, A, toward the right in the direction of the arrow. Thereby the matrices are shifted from the dotted line position, Fig. 4^b, to the full line position of the same figure, so that their notches 8 engage the strip 9. By this engagement of the matrices the matrix basket A is coupled and thrown into gear. For the above operation see particularly Figs. 1, 4 and 5. Under these conditions the pin

15 is not advanced, however, since on depressing the coupling rod 16 the lever 44 is rocked into such a position that it cannot actuate the other levers. Hence, by pressing on the coupling rod, 16, both the matrix basket and the machine are coupled. Thereupon, the automatic casting takes place and the machine is then unclutched in a manner well known in this art. The matrices are 10 thereupon distributed by unclutching the matrix-basket and swinging the same backward. The fillet 26 comes first into action and preliminarily adjusts the matrix-bars; the levers 11 then act, which adjust the matrix-bars in a vertical direction, and the line 15 is then cast. After the casting is effected the mold-holder 10 rocks backward, whereby the hook 37 rocks the two-armed lever 30 and with it puts the basket out of gear, 20 that is to say, shifts it to the left, as above explained. Fillet 26 rocks back again and the levers 11 simultaneously come out of the grooves 7. By swinging the basket the matrix-bars are then put aside.

25 If mixed matter is to be composed, commencing in the first place with a word in slender type, the manner of working is the same as above described. If a word is then to be composed in full-faced type, the matrix-basket must be thrown into gear, or shifted to the right. This is effected by rotating the coupling-rod 16 and with it the cam 17 thereby depressing the arm 32, so that the spring 28 can displace the basket, 30 the consequence of which is that the pin 15 is simultaneously pushed forward, because the basket under these conditions strikes against the carriage 19 and shifts the same. The slanting face 14 is also simultaneously pushed forward by the rotation of the cam 17. If the keys are now depressed, the matrix-bars run up the slanting face and are thus raised, so that the lower matrix comes into the position for casting. The 35 matrix-bars are, however, held by the projecting pin 15 and prevented from running on to the strip 9. If the word which is to be cast in full-faced type is then composed, the matrix-bars forming this word are then 40 pushed on to the strip 9, the pin 15 being withdrawn. This is effected by pressing on the space-key, whereby the pin 15 is withdrawn by means of the rod 63, and the arm 66 is simultaneously pressed forward, so 45 that it pushes the matrix-bars forward. When the space-key is released, the pin 15 is pressed forward again. A second word can then be composed in full-faced type. The slanting face 14 is provided with tooth-like projections 67. The purpose of these 50 is to prevent the matrix-bars, which fall down with great force and strike against the pin 15, from rebounding and becoming set irregularly in consequence. When the 55 complete line has been composed, the ma-

chine must be coupled and the pin 15 simultaneously withdrawn, because otherwise the movable parts, the flag-staff, the casting device, etc., would collide with the said pin 15. This coupling of the machine and withdrawal of the pin is effected by depressing the coupling rod 16. If the next word is now to be composed in slender type, it is necessary that the slanting face 14 be withdrawn. This is effected simply by rotating the coupling-rod 16 and the cam 17 backward, in consequence of which the two-armed lever 18 can rock backward under the action of the spring 43. The matrix-bars then fall again against the pin 15, 80 they are, however, not raised, and after a word is composed are pushed together on to the strip 9 by depressing the space-key.

In order to prevent the basket being turned up before it is thrown out of gear, 85 or shifted to the left, whereby the matrix-bars and wires would become torn, by reason of being held by the strip 9 which engages the notches 8 thereof (see Fig. 4^b) the machine is so arranged that the said 90 basket cannot be thrown up when such engagement occurs. For this purpose a hook or angle-iron 68 (Figs. 4 and 6) is attached to the fixed frame B under which a pin 69 on the matrix-basket engages as soon as 95 the basket is put into gear. It can be turned up when the pin comes out of engagement with the iron 68. The basket may also be displaced by hand.

Under the present invention, it will be 100 seen that the matrix-bars, whether they be designed to cast from the upper or lower matrices 12,13, will first be adjusted horizontally on the guide-strip 9, which loosely engages the notches 8 or 8', and thereupon the 105 said matrices are adjusted vertically and transversely to the line of composition by the lever 11 and the fillet 26, the former serving to raise the matrices to the extent of their play, so that the lower shoulders 110 of the notches 8 or 8' will bear against the under surface of the guide-strip 9. Thereby, the matrices are brought into the proper position in front of the mold. Where type are to be cast from the lower matrices 13, 115 each group of matrices, from which the lower characters are to be cast, is first raised by the slanting face 14 and is also brought out of line with the normal line of composition by throwing the matrix basket into 120 gear. In this position the lower notches 8' are brought opposite to the guide-strip 9. When the group to be cast with the lower matrix characters has been assembled, the said group is then shifted transversely to 125 the line of composition by throwing the matrix basket out of gear, thereby causing the notches 8' to loosely engage the said guide-strip 9. The other operations for adjusting the bars vertically, so that the 130

lower shoulders of the notches 8' all bear against the strip 9, are the same as when casting from the upper matrices.

What I claim as my invention and desire 5 to secure by Letters Patent is:—

1. In a composing machine, a series of matrix-bars and guiding wires for the same, in combination with means for assembling the matrix-bars in line, and means for adjusting the line of matrix-bars horizontally, and also for adjusting the said matrix-bars vertically and transversely after assembling them in line, and before causing them to engage the mold.

15 2. In a composing machine, the combination of a frame and matrix-bars, each having a plurality of matrices, means for assembling matrix-bars in line thereon, with means on said frame for adjusting said line of matrix-bars horizontally, and for adjusting the said matrix-bars vertically and transversely after assembling them in line, and before causing them to engage the mold.

25 3. In a composing machine of the type described, the combination of a frame, means for assembling matrix-bars in a line thereon, each of said matrix-bars having an incision on its front longitudinal edge and a notch on its rear longitudinal edge, a strip fixed on said frame, and means on said frame adapted to engage said matrix-bars in said incisions and adjust the same horizontally and transversely to the line of composition against said strip, whereby said strip 30 and said notches interlap.

4. In a composing machine, a series of matrix-bars and guide-wires for the same, in combination with means for assembling the matrix-bars in line, means for adjusting the line of matrix-bars horizontally, means for shifting the said line of matrix-bars transversely to the line of composition, and for adjusting the matrix-bars vertically, and before causing them to engage the mold.

45 5. In a composing machine of the type described, the combination of a frame and matrix-bars each having a plurality of matrices, means for assembling the matrix-bars in a line thereon, means for positively shifting said line of matrix-bars transversely to the line of composition, and for adjusting the matrix-bars vertically and before causing them to engage the mold.

6. In a composing machine of the type described, the combination of a frame, means for assembling matrix-bars in a line thereon, the edge of each matrix-bar having an incision on its front longitudinal edge and a notch on its rear longitudinal edge, a strip 55 fixed on said frame, means on said frame adapted to engage said matrix-bars in said incisions and to adjust the same horizontally, and means for positively shifting the said matrix-bars transversely to the line of composition against the strip.

7. In a composing machine, a series of matrix-bars having two matrices arranged one above the other and guiding-wires for the same, in combination with means for assembling the matrix-bars, means for raising a group of bars, means for adjusting the group horizontally, means for shifting them transversely to the line, and for adjusting the matrix-bars vertically and before causing them to engage the mold.

75 8. In a composing machine, a series of matrix-bars having two matrices arranged one above the other on one side and corresponding notches at the opposite side, and guiding wire for the same, in combination with a guide-strip adapted to loosely engage one of the said notches of each matrix-bar during the assembling operation, in combination with means for adjusting said matrix-bars transversely to the line of composition and to adjust the same vertically to said line to press the lower shoulders of the engaged notches to bear against the guide-strip, before causing the matrix-bars to engage the mold.

80 9. In a composing machine of the type described, the combination of a frame, means for assembling matrix-bars in a line thereon, each of the said matrix-bars having an incision on its front longitudinal edge and a notch on its rear longitudinal edge, a strip fixed on said frame, and a rocking "flag-staff" having a fillet on said frame, said fillet being adapted to engage said matrix-bars in said incisions and to adjust said bars 85 horizontally against said strip.

10. In a composing machine of the type described, the combination of a frame, means for assembling matrix-bars in a line thereon, each of said matrix-bars having an incision 105 on its front longitudinal edge and a notch on its rear longitudinal edge, a shaft on said frame, a strip fixed on said frame, and means actuated from said shaft adapted to engage said matrix-bars in said incisions and press the same vertically against said strip, whereby said strip and said notches interlap.

11. In a composing machine of the type described, the combination of a frame, means for assembling matrix-bars in a line thereon, each of said matrix-bars having an incision on its front longitudinal edge and a notch on its rear longitudinal edge, a shaft on said frame, a strip fixed on said frame, and a lever (11) actuated from said shaft adapted to engage said matrix-bars in said incisions and to press said bars vertically against said strip.

12. In a composing machine of the type 125 described, the combination of a frame, means for assembling matrix-bars in a line thereon, each of said matrix-bars having a plurality of matrices and a corresponding plurality of incisions on its front longitu-

nal edge and a corresponding plurality of notches on its rear longitudinal edge, a shaft on said frame, a strip fixed on said frame, and means actuated from said shaft adapted to engage said matrix-bars in said incisions and press the same horizontally and vertically against said strip, whereby said strip engages in said rear notches.

13. In a composing machine of the type described, the combination of a frame, means for assembling matrix-bars in a line thereon, each of said matrix-bars having a plurality of matrices and a corresponding plurality of incisions on its front longitudinal edge and a corresponding plurality of notches on its rear longitudinal edge, a shaft on said frame, a strip fixed on said frame, a "flag-staff" having a fillet adapted to rock on said frame and adapted to engage said matrix-bars in said incisions and to justify said bars horizontally against said strip, and a lever actuated from said shaft adapted to engage said matrix-bars in said incisions and to justify said bars vertically against said strip.

14. In a composing machine of the type described, the combination of a fixed frame, a movable frame mounted pivotally thereon, a matrix-receptacle revoluble on said movable frame, a strip fixed on said former frame, a stop (15) movable on said fixed frame, means on said receptacle for assembling matrix-bars in a line on said fixed frame in front of said stop, means for moving said stop into the path of said line of matrix-bars, means for withdrawing said stop away from said line of matrix-bars, and means for transferring the assembled line of matrix-bars on to fixed strip after said stop is withdrawn.

15. In a composing machine of the type described, the combination of a fixed frame, a movable frame mounted pivotally thereon, a matrix-receptacle revoluble on said movable frame, a strip fixed on said former frame, a stop (15) movable on said fixed frame, means on said receptacle for assembling matrix-bars in a line on said fixed frame in front of said stop, means operable by said receptacle for moving said stop into the path of said line of matrix-bars, means for withdrawing said stop away from said line of matrix-bars, and means for transferring the assembled line of matrix-bars on to said fixed strip after said stop is withdrawn.

16. In a composing machine of the type described, the combination of a fixed frame, a movable frame mounted pivotally thereon, a matrix-receptacle revoluble on said movable frame, a strip fixed on said former frame, a stop (15) movable on said fixed frame, means on said receptacle for assembling matrix-bars in a line on said fixed frame in front of said stop, an inclined

track movable on said fixed frame, means for moving said track and said stop simultaneously into the path of said line of matrix-bars, means for withdrawing said stop and said track away from said line of matrix-bars, and means for transferring the assembled line of matrix bars on to said fixed strip after said stop and said track are withdrawn.

17. In a composing machine of the type described, the combination of a fixed frame, a lever pivoted thereon, another frame mounted revolubly and connected with one end of said lever, a matrix-receptacle on said latter frame, and means on said receptacle for assembling matrices on said fixed frame.

18. In a composing machine of the type described, the combination of a fixed frame, a lever (30) pivoted thereon, a spring-pulled shaft (1) movable in said frame, a matrix-basket on said shaft, an arm pivotally connecting said shaft with one end of said lever, a locking device on said frame adapted to hold the other end of said lever, and means for releasing said locking device whereby said basket is displaced.

19. In a composing machine of the type described, the combination of a fixed frame, a lever (30) pivoted thereon, a spring-pulled shaft (1) movable in said frame, a matrix-basket on said shaft, an arm pivotally connecting said shaft with one end of said lever, a lever (32) on the end of said former lever adapted to abut against said fixed frame and lock said former lever, and a coupling-rod adapted to operate said lever (32) and release the same from said fixed frame, whereby said basket is displaced.

20. In a composing machine of the type described, the combination of a fixed frame, a lever (30) pivoted thereon, carrying a stop (38), a spring-pulled shaft (1) movable in said frame, a matrix-basket on said shaft, an arm pivotally connecting said shaft with one end of said lever, a shaft (23) revoluble in said fixed frame, a mold-holder on the latter shaft, and a hook revoluble on said mold-holder adapted to engage said stop (38).

21. In a composing machine of the type described, the combination of a fixed frame, a lever (30) pivoted thereon, carrying a stop (38), a spring-pulled shaft (1) inovable in said frame, a matrix-basket on said shaft, an arm pivotally connecting said shaft with one end of said lever, a shaft (23) revoluble in said fixed frame, a mold-holder on the latter shaft, a hook revoluble on said mold-holder adapted to engage said stop (38), and means to prevent said hook engaging said stop (38).

22. In a composing machine of the type described, the combination of a fixed frame, a lever (30) pivoted thereon, having a slot and carrying a stop (38), a spring-pulled

- shaft (1), movable in said frame, a matrix basket on said shaft, an arm pivotally connecting said shaft with one end of said lever, a shaft (23) revoluble in said fixed frame, a 5 mold-holder on the latter shaft, a hook revoluble on said mold-holder adapted to engage said stop (38), and a lever-actuated rounded face (40) in said slot adapted to prevent said hook engaging said stop (38).
- 10 23. In a composing machine of the type described, the combination of a fixed frame, a lever (30) pivoted thereon, a spring-pulled shaft (1) movable in said frame, a matrix-basket on said shaft, an arm pivotally connecting said shaft with one end of said lever, a lever (32) on the end of said former lever adapted to abut against said fixed frame and lock said former lever, and a coupling-rod, carrying a cam having a 15 slanting face, adapted, when rotated, to operate said lever (32) and release the same from said fixed frame, whereby said basket is displaced.
- 20 24. In a composing machine of the type described, the combination of a fixed frame, a movable frame mounted pivotally thereon, a matrix-basket revoluble on said movable frame, means on said basket for assembling matrix-bars in a line on said fixed frame, a 25 stop (15) movable on said fixed frame adapted to move in front of the assembled line of matrix-bars, a coupling-rod mounted revoluble on said basket, a cam on said rod, and levers, substantially as shown, connected 30 with said stop and adapted to be operated by said cam when the same is rotated.
- 35 25. In a composing machine of the type described, the combination of a fixed frame, a movable frame mounted pivotally thereon, a matrix-basket revoluble on said movable frame, means on said basket for assembling matrix-bars in a line on said fixed frame, a 40 stop (15) movable on said fixed frame adapted to move in front of the assembled line of matrix-bars, and levers (44, 46, 20), substantially as shown, connected with said stop and adapted to be operated by said basket when the same is displaced away from said fixed frame.
- 45 50 26. In a composing machine of the type described, the combination of a fixed frame, lever mechanism (44, 46, 20) mounted thereon, a matrix basket movable on said frame, a coupling-rod on said basket, a hook on 55 said coupling-rod adapted to engage said lever mechanism, for the purpose specified.
27. In a composing machine of the type described, the combination of a fixed frame, a stop thereon, a matrix-receptacle mounted on said frame, means on said receptacle for assembling matrix-bars in a line on said frame against said stop, a space-key on said receptacle, and a lever (66) actuated by said space-key adapted to push said matrix-bars, as set forth. 60
28. In a composing machine of the type described, the combination of a fixed frame, a stop thereon, a matrix-receptacle, mounted on said frame, means on said receptacle for assembling matrix-bars in a line on said frame against said stop, a space-key on said receptacle, and a rod (63) actuated by said space-key and adapted to displace said stop, as set forth. 65
29. In a composing machine of the type described, the combination of a fixed frame, a movable frame mounted pivotally thereon, a matrix-receptacle revoluble on said movable frame, a strip fixed on said former frame, a stop (15) movable on said fixed frame, means on said receptacle for assembling matrix-bars in a line on said fixed frame in front of said stop, an inclined track, having projections, movable on said fixed frame, means for moving said track 80 and said stop simultaneously into the path of said line of matrix-bars, means for withdrawing said stop and said track away from said line of matrix-bars, and means for transferring the assembled line of matrix-bars on to fixed strip after said stop and said track are withdrawn. 85
30. In a composing machine of the type described, the combination of a fixed frame, a lever (30) pivoted thereon, a spring-pulled shaft (1) movable in said frame, a hook on said frame, a matrix-basket on said shaft, an arm pivotally connecting said shaft with one end of said lever, a locking device on said frame adapted to hold the other end of said lever, means for releasing said locking device whereby said basket is displaced, and a pin on said basket adapted to engage said hook when said basket is displaced. 90
